UNITED STATES PATENT OFFICE

THOMAS C. SPELLING, OF NEW YORK, N. Y.

WATER HOIST

Application filed February 25, 1929. Serial No. 342,653.

This invention relates to certain new and useful improvements in water hoists, and deals particularly with a device for hoisting from a lower to a higher level large quantities of water, for storage, or to furnish a constant supply, and provides means for emptying a container of its liquid contents during continuous forward movement.

As pointing to the utility of the invention, 10 attention is called to the fact that there is general interest in and discussion of uses for water including household, municipal, irrigation, stock-watering and mining uses, and especially for generating power.

15 The object of this invention most simply stated is the provision of means for utilizing water for a variety of uses, which need not be here further specified.

Other objects and aims of the invention, 20 broader or narrower according to conditions and circumstances, than those stated above, together with the advantages inherent, will be in part obvious, and in part specifically referred to in the course of the following description of the elements, combinations, arrangement of parts and application of principles constituting the invention; and the scope of protection contemplated will appear from the appended claims.

25 In the accompanying drawings which form a part of this specification, similar letters of reference indicate like parts throughout the several views, in which:

30 Figure 1 is an assembly side view, some 35 of the shell of the container being broken away to uncover interior parts, and exhibiting those parts.

Figure 2 is a sectional view taken centrally through one of a series of quadrangular supports and through other parts.

35 Figure 3 is a perspective of a container of a somewhat different arrangement from that shown in Fig. 1, showing applicability thereto of the proposed improvements.

40 Figure 4 exhibits the equipment on the margin of and beneath a slit in the rear wall of the container.

45 Figure 5 is a detached view of an element designed to prevent leakage around the ends 50 of a cross-bar.

Figure 6 is a sectional view to show overlapping positions of a lobe and flap.

Figure 7 is a view exhibiting a slit under the rear wall of the container and the relative positions of parts.

55 Figure 8 shows an extension on the margins of an opening in a side of the container, of a slit and pliable filling therefor, the latter being shown under the rear wall of the container.

60 For a better understanding, I begin with a comprehensive description of certain essential parts and their modes of functioning, without reference to the figures or designating letters. The power is applied to an endless flat linked chain and will move it up one side and down the other and around on an 65 endless sextangular frame. To the chain are attached containers for water—possibly for other liquids—and these are carried, each in 70 succession upward to a point at which it is emptied into a basin. Without even pausing, the carrier is moved around and over the apex of the frame and downward to the body of water constituting the source of supply. 75 Continuing the forward movement, each carrier is drawn through the water and around the lower end of the frame, shown in the drawing in submergence, and filled. Continuing the forward movement, it is again 80 drawn upward. Stationary rollers are placed at points shown in the drawings on the upper and lower terminals of the frame. These rollers are axled into the frame and 85 may be formed of iron, steel, wood, or other hard substance, and be provided with coverings of vulcanized rubber or other suitable material between the flanges, to accommodate slight contractions or extensions of the chain due to variations in temperature. 90 These coverings also serve to keep the chain taut.

95 In the hoists which have heretofore come to my notice, the wheels to which power was applied were located either in the extreme apex or in adjacent angles. Here, for convenience in operating the mechanism, the toothed wheels, 95, are located immediately above the base, and instead of the power chains extending obliquely upward, they here 100

extend around the power wheels horizontally. Both, upon application of power, turn from left to right, thus cooperating to equalize strain on the structure. The drawings exhibit here a support for the basin which in turn is supported on the main support for the structure. The latter penetrates the earth or other substance underlying the liquid supply. But, obviously, where it is desirable 5 to hoist water from a canyon or subterranean source of supply a bridge or other superstructure could be built above the hoist and its equipment, and the structure attached to that for support.

10 It is deemed unnecessary to particularly describe or illustrate the shifting means whereby a sliding door is shifted from its position over the opening in the nether side of a container and released. It will suffice to 15 state that such means consists of members stationed oppositely beyond the path of the container, near one terminal of a horizontal portion of the frame. A pivoted catch, in the one form and an arm in an alternative form, 20 is struck by ends of a cross-bar carried by the container, and after having been thus moved in slots, is automatically released by means carried on the container and; thereupon the sliding door is pulled back into its former 25 position by the action of springs, the functioning of the springs being hereinafter described.

30 Nor is any detailed reference to any antecedent superstructural guide necessary. The following is a description of the present improvement, illustrated in Figure 2. The supports, 59, constitute a series extending, at proper spaces from each other, all around the frame. They are attached to the nether 35 portions of the sides of the frame at 60, form angles beyond the path of the container and extend over across its path. Centrally, is attached to the series of supports the member, 61, which extends all around the frame, 40 equidistant from it, at all points. To each container is attached the guide member, 62, carrying, axled into its bifurcated ends, the horizontally positioned rollers, 63. In order 45 to secure constant engagement of the rollers with the interior surfaces of the member, 61, the short folding spring, 64, is placed interiorly between the two portions of the bar 65. The parts of the bar are of quadrangular shape, and are positioned in, but not attached 50 to, the socket 66. The portions of the bar are secured together by the spring 64. In putting together the parts, the spring will be 55 compressed. Thus steady engagement on the one hand will be secured and, on the other, 60 swaying of the container prevented.

The next improvement to be described is a speedier means for emptying the container than any that is provided in any hoist heretofore invented, planned or used. That here 65 provided will allow the content to almost in-

stantly drop out, thus allowing speedy movement of the endless chain. Here is provided an opening almost coextensive with the entire area of the lower side, and a sliding door to correspond. Obviously, such a result involves mechanism extending beyond the interior of the container, and such provision is here made.

The container shown in Fig. 1 is constructed with chambers in or attached to the front wall exteriorly. Very little explanation of the functioning of the coiled wires contained within drums, 69, is needed, beyond what the drawing discloses. The form, function, action and reaction of the wires, to contain which the cylindrical drum, 69, is provided, are matters too well known to those skilled in the art to require its detailed description. Hence, only the part, 71, attached to the cross-bar, 74, is exhibited. Obviously, 75 the chambers in which the drums are positioned open into the interior of the container. There are two of the drums and contained wires, each wire suitably attached to the cross-bar. Upon being actuated by the exterior 80 mechanisms, the wires exert a retarding force. At rest, the attachment of the wires to the cross-bar is on each side near the front end of the container, and, in operation, the wires are uncoiled and stretched by the backward 85 movement of the cross-bar, 74, and sliding door, 75.

In the rear wall of the container is formed the narrow opening, 76, through which a short length, 73, of the sliding door protrudes, even when it is stationary, that is to say, after being pulled back by reaction of the wires. See Fig. 4. The opening, 76, extends to the basic surface of the container. To prevent leakage during the upward movement of the container on the frame, two parts of soft rubber or other flexible material are employed. The one part, 77, is slotted through its upper portion and sides, and into the slit is fitted and secured the top and side 100 margins of the end wall. Directly under such rubber attachment is fitted into a narrow recess in the base of the container the strip, 78, formed of soft rubber or other flexible material. These rubber parts are 105 adapted to press down and up, respectively, sufficiently to prevent leakage, but not sufficiently to produce such friction as to retard the movement back and forth of the sliding door. The rubber strip, 78, yields under the 110 weight of the sliding door, especially while the container contains liquid, so that the contact of the sliding door with the integral margin of the interior of the container is not interfered with.

The recess under the aforesaid opening in the rear is extended in and along the integral margin at the sides and across the front end of the nether side of the container as shown in Figure 8. The same filling of soft 115

rubber or other pliable material occupying the recess under the rear wall also occupies the extension, and for the same purpose, namely, prevention of leakage. The rubber or other flexible material in the extension is given the reference number 101.

When the cross-bar, pushing out the sliding door is forced back to the position seen in Figure 1, it is temporarily locked or scotched there during the outflow of liquid by the combined action of the down flowing liquid and the apron, 79, shown in Figure 1. The apron is secured in place by the hook members, 80, attached to the rear wall, allowing its free vertical movement. It is supported in horizontal position by the slender springs, which are given the reference number, 81, in Fig. 1, and are likewise supported on and extend out from the rear wall of the 20 container. As here shown, they are bent back against adjacent parts. To prevent the apron falling back against the rear wall during the movement of the container around the frame, and being thus prevented from functioning, 25 the slender rigid bars, 82, also supported on the rear wall, are positioned above it, as seen in the drawing.

Simultaneously with the arrival of the cross-bar at the point shown in Figure 1, 30 the apron is forced down by the downpour of liquid on and against it, whereby the return movement of the cross-bar, otherwise immediately responsive to the reaction of the wires, 71, is delayed. Obviously, upon removal of the pressure on the apron, the slender springs, 81, push it back to horizontal position.

Means are also provided for preventing leakage around the terminals of the cross-bar, 74. The flaps, 83, are attached to upper margins of slots, 84, illustrated in Figure 5. Lobes, 85, are secured to the adjacent inner margins of the slots, as shown in Figure 5 and operation of the mechanism causes the lobes to exert downward pressure on the ends of the cross-bar. I provide here also, the underlying strip, 86, which rests in a recess in the base of the container, and the combined effect of lobe and strip is the prevention of leakage at that point, very similarly as it is prevented at the rear, as above explained. At the junction of the flaps and lobes, they are oppositely tapered, as shown in Figure 6, the flaps tapering inwardly and the lobes outwardly. Thus they are adapted to cooperate in preventing leakage, without interference with respective functions; and the downward pressure of the lobes insures frictional contact of the sliding door with integral margins of the container.

Another improvement has for its object means for accelerating the downflow and exit of the liquid content of the container. It is evident that the speedier current at the centre of the outflow, and adjacent thereto, and

in diminishing degrees as the distance from the center increases, will, to some extent, obstruct the sections or portions of liquid content at the sides and in the corners; and especially in those chambers constructed for the emplacement of the drums and wire members designed to pull back the cross-bar and sliding door. To offset or overcome the tendency just mentioned, the obliquely slanted partition, 87, is provided and attached to the sides and front wall, as seen in Figure 1. It is observable that to this objective effect the apron, 79, at the rear end also contributes, thus performing the double function of temporarily scotching the cross-bar and of diverting the main stream toward the centre, allowing those portions of content below and behind it to run out, simultaneously with the main stream, thus functioning for the rear end as the partition functions for the front. In other words they function in combination.

A modification is illustrated in Fig. 3, to show the applicability of elements embodied in the main invention to a container of somewhat different form. Therein, the opening under the sliding door, 67, extends only approximately one-half the length of the container, and the sliding door corresponds in dimension proportionately. The door and interior actuating means are entirely within the container. The parts illustrated are differentiable from the same parts as shown in Fig. 1 only as regards positions and supports for the hook members, slender rigid bars, and slender springs, here shown at rest, with the reference number, 93. In other words, whereas in Fig. 1 the apron and its equipment are supported on the rear wall, here they are supported on the rear partition near its lower edge. The rear partition terminates just above the path of the cross-bar and sliding door. It will be noted that, whereas in Fig. 1 the cross-bar when actuated pushes, here it pulls back the sliding door. A technical description may be given as follows:

The partitions, 88 and 92, are supported on the interior rear and sides of the container. To the partition 88, near its lower terminal are secured the hooks, 91, on which is suspended the apron, 89. The apron is supported below by the slender springs, 93, and its backward movement is checked by the slender rigid bars, 94, all being supported on the partition. The apron here functions to scotch the front edge of the sliding door, in the downpour of liquid, as does the corresponding member to scotch the cross-bar in the principal form. Here, unlike Fig. 1, a triangular section, 90, is removed from the apron so as to allow it to straddle, in operation, a watershield which is an element in such mechanisms, and which, when emplaced,

would otherwise obstruct the movement of the apron.

Very little remains to be added concerning the actuating elements of the invention.

5 In the position here assigned it, the toothed wheel 95, and the larger pulley wheel, emplaced on a common axle 96 positioned in a portion 98, of the frame, suitably formed, will be nearer the operator of the mechanism than if the actuating means were located in 10 upper angles. A mere fragment of the chain, 97, is here shown; and even that is omitted on the right hand side in order to exhibit part, 98. It may be again properly remarked that both toothed wheels, 95, are 15 designed to turn to the right. The container is supported on and attached to the chain as indicated in Figure 1.

Detailed description of the supporting 20 structure for the entire mechanism is here omitted, and for the reasons already stated. The support for the basin, 100, exhibited in Figure 1, in fragmentary form, will, in a complete hoist, be supported on the support 25 for the entire hoist.

What I desire to secure by United States Patent is:

1. In an apparatus of the character described, a container for liquids having an 30 open discharge portion and a slotted end wall, and a sliding closure for the discharge portion adapted to move through said slotted end wall in opening the discharge portion, in combination with sealing means at the 35 slotted end portion of the wall cooperatively related to the sliding closure to prevent leakage therebetween.

2. In an apparatus of the character described, a container for liquids having a bottom 40 discharge portion adapted to be opened for substantially the full extent of the bottom of the container, a closure for said discharge portion, and means for supporting said closure whereby the same may be bodily 45 withdrawn beyond one wall of the container, in combination with means for automatically returning the closure to closed position when the container is emptied, and means adapted to be influenced by liquid discharging from the 50 container for restraining the closure in open position in opposition to the action of the closure returning means.

3. In an apparatus of the character described, a container for liquids having a bottom 55 discharge portion, a closure for said discharge portion, means for automatically closing and normally maintaining the closure in closed position, and means adapted to be influenced by the liquid discharging from the 60 container for restraining the closure in open position against the action of the closing means.

4. In an apparatus of the character described, a container for liquids having a bottom 65 discharge portion, a closure for said dis-

charge portion, means for automatically closing and normally maintaining the closure in closed position, and means adapted to be influenced by the liquid discharging from the container for restraining the closure in open position against the action of the closing means, said last mentioned means comprising a yieldable apron arranged to be forced downwardly by discharging water into the path of return movement of the closure. 70

5. In an apparatus of the character described, a container for liquids having a bottom discharge portion, a closure for said discharge portion, means for automatically closing and normally maintaining the closure in closed position, and means adapted to be influenced by the liquid discharging from the container for restraining the closure in open position against the action of the closing means, said last mentioned means comprising a yieldable apron arranged to be forced downwardly by discharging water into the path of return movement of the closure, 75 said yieldable apron having means for restoring the same to normal position out of said path when the influence of the liquid on the apron is removed. 80

6. In an apparatus of the character described, a container for liquids having a bottom discharge portion, a closure for said discharge portion, means for automatically closing and normally maintaining the closure in closed position, and means adapted to be influenced by the liquid discharging from the container for restraining the closure in open position against the action of the closing means, said last mentioned means comprising a yieldable apron arranged to be forced downwardly by discharging water into the path of return movement of the closure, 90 said apron being elongated to serve when forced downwardly as an inclined deflector to direct the discharging liquid to a predetermined zone of escape. 95

7. In an apparatus of the character described, a container for liquids having a bottom discharge portion, a closure for said discharge portion, means for automatically closing and normally maintaining the closure in closed position, and means adapted to be influenced by the liquid discharging from the container for restraining the closure in open position against the action of the closing means, said last mentioned means comprising a yieldable apron arranged to be forced downwardly by discharging water into the path of return movement of the closure, 100 said apron being elongated to serve when forced downwardly as an inclined deflector to direct the discharging liquid to a predetermined 105 zone of escape, the apron or deflector being notched at its free or lower end to accommodate a water shed or the like. 110

8. In an apparatus of the character described, a container for liquids having a bot- 115

tom discharge opening, a closure therefor, and means adapted to be controlled by the liquid discharging from the container for directing said discharging liquid to the intended zone of escape.

5 9. In an apparatus of the character described, a container for liquids having a bottom discharge opening, a closure therefor, and means adapted to be controlled by the liquid discharging from the container for directing said discharging liquid to the intended zone of escape, said means comprising a self-restorable apron or deflector de-
10 pressible into directing position by the weight of the discharging liquid thereagainst.

10 10. In an apparatus of the character described, a container for liquids having a bottom discharge opening, a closure therefor, and means adapted to be controlled by the liquid discharging from the container for directing said discharging liquid to the intended zone of escape, said means comprising a self-restorable apron or deflector de-
20 pressible into directing position by the weight of the discharging liquid thereagainst, in combination with an oppositely disposed deflector cooperatively related to said first mentioned deflector whereby the discharging liquid is directed towards a relatively centrally disposed zone of escape.

25 11. In an apparatus of the character described, a liquid container having an open bottom, means for carrying the container in approximately vertical and horizontal directions, a slidable closure for the open bottom withdrawable in the direction of one end of the container, a hinged apron adapted to be forced, by discharging water, through the opening when permitted by withdrawal of
35 the closure, a spring for restoring the apron to normal position away from the path of closing movement of the closure when the container is emptied, and means for preventing displacement of the apron from operating position when the container is travelling through its vertical to its horizontal position.

40 12. In an apparatus of the character described, a container having an open bottom portion, a sliding door therefor, means at one end of the container operatively associated with the sliding door for closing the latter, and a deflector in the container overhanging said end thereof to direct the discharging liquid away from the same.

45 13. In an apparatus of the character described, a container having an open bottom portion, a sliding door therefor, means at one end of the container operatively associated with the sliding door for closing the latter, and a deflector in the container overhanging said end thereof to direct the discharging liquid away from the same, said closing means including a drum at said end
50 of the container, retracting spring means,

and suitable connections with the sliding door.

14. In combination, a container having a bottom discharge portion, a closure therefor, and oppositely arranged aprons or deflectors in the container adapted, when the closure is open, to direct the discharging material to a relatively central point.

15. In combination, a liquid container having a bottom discharge portion, and slotted sides, a sliding door for the discharge portion having actuating parts working in said slotted sides, and means for sealing the path of movement defined by the slotted portions, said sealing means including oppositely beveled separately engaging flexible sealing strips.

16. In combination, a liquid container having a bottom discharge portion and slotted sides, a sliding door for the discharge portion having actuating parts working in said slotted sides, and means for sealing the path of movement defined by the slotted portions, said sealing means including lobe-like yieldable packing portions engageable with the door actuating parts, substantially as and for the purpose described.

17. In a machine of the character described, a framework, a carrier working thereon, a container on said carrier, oppositely disposing guiding members, and yieldable antifriction bearing members on the carrier engageable with said guiding members, substantially as and for the purpose described.
